ELECTRIC PRESSING IRON

Stanley Wallace, Chicago, Ill.

Application July 11, 1939, Serial No. 283,860

25 Claims. (Cl. 38—77)

The present invention relates in general to electric pressing irons, and more in particular to an iron of this character which is provided with means for generating steam which is injected into the goods while the iron is in use. The main object of the invention is to provide a new and improved steam iron.

In some respects the steam iron disclosed herein may be considered as an improvement on the iron shown in my copending application, Ser. No. 143,031, filed May 17, 1937.

The invention includes a considerable number of improvements which cooperate in producing a steam iron which is entirely safe, free from trouble, and more satisfactory to use than steam irons heretofore available. The invention and the various features thereof will be described in detail hereinafter, reference being had to the accompanying drawings, in which:

Fig. 1 is a sectional view of the complete steam iron, taken on the line 1—1, Fig. 2;

Fig. 2 is a section through the boiler, taken on the line 2—2, Fig. 1;

Fig. 3 is partly a top view and partly a section of the sole plate, the section being on the line 3—3, Fig. 1;

Fig. 4 is a section through the terminal housing taken on the line 4—4, Fig. 1;

Fig. 5 is a section through the water tank and water control valve, taken on the line 5—5, Fig. 1;

Fig. 6 shows a modification and is a side view of the back part of the iron, with a part of the water tank in section to show a different form of water control valve mechanism;

Fig. 7 shows another modification, and is a section through a part of the boiler and the water control valve; and

Fig. 8 shows a modified form of cap which may be used for the water tank, in case a continuous supply of water to the tank is desirable.

Referring to the drawings, the sole plate 2, Figs. 1 and 3, may be somewhat similar in construction to the one shown in my co-pending application. It has a recess 3 extending from the toe along both sides to receive the lower edge of the cover. On the upper side of the sole plate there is a recess 4, in which the thermostatic control mechanism is mounted, as will be described presently. The reference numeral 5 indicates a channel constituting a steam passage, the shape of which is clearly shown in Fig. 3. Outlets such as 6 extend from the steam passage to the face of the iron.

The boiler 1 is shown in Figs. 1 and 2. It is a

one-piece casting, and has a main steam-generating cavity 8, which may be filled with copper wool or similar material. Access to the cavity 8 is had through two openings at the top which are normally closed by threaded plugs 13 and 14. Partitions 9 and 10 extend from opposite sides part way across the cavity 8, and the latter partition is enlarged at 11 to provide room for the opening 12 in which the shaft 138 of the adjusting device for the thermostatic control mechanism is located. Near the forward end of the boiler a hole is drilled up from the bottom and is tapped to receive the threaded tubular member 15. The lower end of member 15 lies in the opening 16 leading to the steam passage 5. A gasket 24 surrounds member 15 and is compressed between the boiler and sole plate, where it prevents the leakage of steam.

The boiler 1 is secured to the sole plate 2 by means of a machine screw 17 in front and by two machine screws such as 18, Fig. 1, at the rear. The latter screws pass down through holes 19 and 20, Fig. 2, in the boiler, and are threaded into tapped holes 21 and 22, Fig. 3, in the sole plate.

The heating element 23 is clamped between the sole plate 2 and the boiler 1. This element is of any suitable and known construction.

The rear part of the boiler, through which the screws 18 pass, is of reduced thickness, as seen from Fig. 1. This part of the boiler comprises two sections 50 and 51 which are joined at the rear by a transversely-extending solid section 52. This construction provides a large opening 53 through which pass the electrical connections to the thermostatic control mechanism. The sections 50 and 51 are hollow, being provided with channels 54 and 55, respectively, which communicate with the main boiler cavity. The transverse section 52 drops down sharply at the rear of the sole plate 2, as seen in Fig. 1, and has a rearwardly-extending section 56. The part 56 merges into the two corner members 57 and 58 which are of slightly increased thickness and are rounded off at the rear, as seen in Fig. 2. The construction just described is of utility in connecting the boiler with the water tank, as will be explained presently.

The boiler is concealed beneath a cover 60, which is cast integrally with the water tank 61. The shape of this casting can be seen from Figs. 1, 4, and 5, also Fig. 6. The cover portion conforms generally to the shape of the main part of the boiler. It is substantially flat on top, with slightly sloping sides, and is brought to a point in

front. The lower edge of the cover fits in the groove 3 of the sole plate 2. Above the rear part of the boiler the cover rises at an angle of about 70 degrees and merges into the water tank. The tank lies to the rear of and partly above the level of the boiler, as seen in Fig. 1. The forward part of the tank extends over the rear depressed portion of the boiler and is recessed in front, as seen in Fig. 4, to provide a housing for the terminal strip.

The combined cover and tank casting is assembled to the boiler and sole plate, as shown in Fig. 1, and is secured in place by means of two screws 62 and 63, which pass through the cover part and are threaded into the boiler, and also by means of two large hollow screws or studs 64 and 65, which pass through the rearwardly-projecting members 57 and 58 of the boiler and are threaded into the bottom of the tank.

There are two passages leading from the water tank to the boiler, one for the admission of water and the other for equalizing the pressure between the boiler and the space above the water level in the tank. These passages extend through the hollow screws 64 and 65.

Describing the pressure-equalizing passage, there is an opening 66 drilled slantingly upward through the overhanging part 52 of the boiler to tap the channel 55. This opening is plugged by a tapered screw 68. Another drilled opening 67 connects the opening 66 with the annular space surrounding the shank or unthreaded portion of the hollow screw 64. The latter is cross-drilled at 71 to afford a communication between the annular space referred to and the hollow interior of the screw, in which is tightly fitted the tube 72. This tube may be made of soft copper and is flexible enough so that the screw 64 can be inserted and tightened up without difficulty with the tube in place. Thus it will be seen that a continuous passage is provided from channel 55 by way of drilled openings 66 and 67, the hollow screw 64 (cross-drilled as explained) and the tube 72 to the space above the water level in the tank. Leakage is prevented by a gasket 70 inserted between the tank and part 58 of the boiler and another gasket 69 beneath the head of screw 64.

The water passage extends through the hollow screw 65, and communicates with the channel 54 of the boiler. From the screw 65 to the channel 54 the water passage is exactly the same as the pressure-equalizing passage just described, and includes the drilled openings 66' and 67', shown in dotted lines in Fig. 2. From the screw 65 in the direction of the tank, the water passage includes a manually controlled shutoff valve 76, Fig. 5, and an automatic shutoff valve 84, Fig. 1.

The manually controlled valve is located in a rounded shoulder 73, Figs. 1 and 5, formed in the wall of the tank. In this shoulder a sloping opening 74 is drilled from the outside and is tapped to receive the threaded portion 78 of the valve 76, the tapered end of which lies in the fine opening 75 which connects the opening 74 with the space above the end of the hollow screw 65. The opening 74 is counter-bored to a large diameter near the top and is tapped to receive the packing gland 77. By means of the latter the packing 79 is compressed around the shank of valve 76 to prevent leakage. The valve 76 is rotated by means of knob 80. By turning this knob in a clockwise direction, the tapered end of the valve may be advanced to completely close the opening 75. Turning the knob in the oppo-

site direction will back off the valve and open it to any desired extent.

The automatic shutoff valve is centrally located in the bottom of the tank, and is shown in Fig. 1. There is a downwardly-projecting annular rim 83 on the outside of the bottom wall of the tank, which is bored out to receive the disk 91. This disk is provided with a central upwardly-extending cylindrical member 85, which is threaded tightly into a tapped opening in the bottom of the tank. The member 85 has a central opening therein through which passes the valve stem 86, the said opening being faced off on top to provide a seat for the valve 84. The valve stem 86 has a threaded connection with a stud which is riveted at the center of the diaphragm 87. This diaphragm is clamped between the disk 91 and the closure member 89, the latter having a short threaded cylindrical portion which enters the tapped interior wall of the annular rim 83. A gasket is provided above and below the diaphragm to prevent leakage. The coil spring 88 normally is under a certain amount of compression, pressing inwardly on the diaphragm 87. Valve 84 is normally open. The vent 90 maintains the lower side of the diaphragm at atmospheric pressure.

A connection between the automatic shutoff valve and the manually controlled valve is established by means of a drilled opening 82 which passes lengthwise through a raised rib 81 on the inside of the bottom wall of the tank. This rib extends from the shoulder 73 diagonally toward the center of the tank where it merges into the annular rim 83. The opening 82 connects with the space 87' above the disk 91 and at the other end it taps the opening 74 at a point which is a short distance above the opening 75. The rib 81 is seen clear in Figs. 1 and 4.

The path for the flow of water from the tank to the boiler may now be traced by way of valve 84, Fig. 1, valve stem opening in 85 to space above diaphragm 87, drilled openings in disk 91 near the base of 85, space 87', drilled opening 82, space in opening 74, Fig. 5, valve 76, cross-drilled hollow screw 65, and openings 67' and 66', Fig. 2, to the channel 54 leading into the main boiler cavity. This path can be closed by valve 76, under control of the operator, and may also be closed by valve 84 responsive to an excessive boiler pressure, as will be explained in described the operation of the iron.

The water tank is filled from the top through an opening which is normally closed by a cap 100. The cap is provided with a gasket so that the opening is sealed with the cap in place.

The handle 102 may be made of wood or of some composition material which is a good heat insulator. It is supported at the rear on a tapered member 101 which projects forward from the upper part of the water tank, and at the front on a bracket 106 which is secured to the cover by screw 62. The handle is in two parts, the main part 102 and a recessed forward part or forecap 103, which are clamped together and to the bracket 106 and member 101 by means of a long bolt 104. This bolt is threaded into a tapped hole drilled in member 101 and when tightened up holds the parts firmly in place. The recessed forward part 103 of the handle partly encloses a bell crank lever 110 which is pivoted at 107 on an ear forming part of bracket 106. Arm 109 of the lever serves to control the steam valve 34. The pin or stud 108 on the other arm of

the lever projects through a slotted opening in the side of handle member 103 and carries a button or knob 111, Fig. 5, by means of which the lever is operated.

The construction of the steam valve may now be explained. This valve is located at the forward end of the boiler, as shown clearly in Fig. 1, in a recess which is formed in the solid toe of the boiler by drilling operations. This recess overlaps the drilled recess for the head of screw 17. The valve includes a main body portion 27, the lower end 28 of which is of reduced diameter and is threaded into the boiler. The member 27 is enlarged at 26 and has a hexagonal head 25 by means of which it may be screwed tightly in place. A gasket is interposed beneath the enlarged rim 26 to prevent leakage. The annular space surrounding the member 27 is connected with the boiler cavity by means of a drilled hole 35. At the bottom of the recess in which the threaded portion 28 is located a sloping hole 36 is drilled to the interior of the tubular member 15.

The body 27 of the valve has a longitudinal bore to receive the valve stem 33, having a valve 34 at the lower end thereof. Leakage around the valve stem is prevented by suitable packing which is compressed by the gland 31. The valve is held closed by a coil spring 30, which is tensioned between the outside face of gland 31 and the nut 29 threaded on the end of the valve stem. This nut affords a means for adjusting the spring tension. The valve stem 33 is of reduced diameter toward the lower end, providing a steam passage which is connected with the space surrounding the valve body 27 by cross-drilling the latter at 32.

The steam valve is opened by operating the knob 111 on pin 108, which rotates the bell crank lever 110 on its pivot 107 and depresses the valve stem 33 against the tension of spring 30. When the valve is open, steam can pass from the boiler to the sole plate by way of opening 35, annular space surrounding 27, cross-drilling 32 in 27, annular space surrounding lower portion of valve stem, valve 34, opening 36, and tubular member 15 to the channel 5 in the sole plate.

It will be noted at this point that the steam valve is so arranged as to act as a safety valve. Steam pressure in the boiler tends to open the valve and if an excess of pressure is built up the valve will open automatically, allowing steam to escape into the sole plate until the pressure is relieved. The pressure at which the valve opens depends on the tension of spring 30, which can be adjusted by means of nut 29, as previously mentioned.

The electrical connections for the iron will now be described briefly. That portion of the front wall of the water tank which lies above the cover is given a U-shaped formation, as seen particularly in Fig. 4, to form a housing for the terminal strip 120, said housing having side walls 121 and 123 and the rear wall 122. The housing projects rearwardly into the tank, as seen in Figs. 4 and 5. The side walls 121 and 123 have vertical slots in which the terminal strip 120 is retained. This terminal strip is of suitable insulating material. The housing is lined with a sheet of insulating material (not shown) to guard against accidental short circuits, and is closed in front by the plate 124.

The cord for supplying current to the iron enters the housing from the right side through an opening 140, Fig. 1, which is formed in the round-

ed inwardly-projecting shoulder 141, seen in Fig. 5. The two conductors of the cord are secured under terminal screws 125 and 126.

The thermostatic control mechanism is mounted on a plate 142, Fig. 1, which is secured at the bottom of the recess 4 in the sole plate by means of screws 136 and 137. The control mechanism comprises a bi-metallic element 134, and contact springs 129 and 130, all of which are secured to plate 142 by means of screw 135. The contact springs are suitably insulated and are provided with contacts 132 and 133 which are normally in engagement. When the bi-metallic element 134 becomes heated, the free end moves upward due to bending of the element and engages the end of screw 143, thereby raising the end of spring 129 to separate contact 132 from contact 133. Screw 143 is adjustable. The working adjustment during use of the iron is accomplished by means of the lever 140, secured to the shaft 138. This shaft has a cam 139 near the lower end which raises or lowers contact 133 responsive to rotation of shaft 138 in one direction or the other, and thus determines the temperature at which the contacts 132 and 133 are separated by the element 134.

The upper contact spring 129 extends to the rear and is bent upward, passing through the opening 53 in the boiler to the terminal strip where it is secured under screw 126. The other contact spring 130 is connected to one end of the winding of the heating element 23. The other end of the heating winding is connected to a metallic strip 128, which extends upward along the back of the terminal strip 120 and is bent over around the top of the strip and retained under screw 125. By the described arrangement the heating element 23 is connected in series with contacts 132 and 133.

40 The operation of the iron will now be described. The knob 80 should first be turned down to close the water valve 76, after which the cap 100 can be removed and the tank filled with water. The cap is then replaced and screwed down tightly. 45 The cord may then be plugged into a convenient receptacle and the iron will begin to heat up. The thermostatic control knob 140 should be set for the desired heat value, depending on the type of material to be ironed.

50 When the iron has become thoroughly heated, the water valve 76 may be opened and water will flow from the tank to the boiler by way of the path described. Since the boiler is hot, steam will be formed at once, but the water continues to flow into the boiler, due to the pressure-equalizing passage including tube 72, which maintains the pressure above the water in the tank equal to the back pressure at the water passage. The opening 75 is rather small and when the valve is fully open, allows only enough water to enter the boiler to provide for the maximum steam requirements. The size of the opening can be reduced by adjustment of the valve.

65 If the steam valve remains closed, the pressure in the boiler will rise gradually, and since the same pressure exists in the tank, the valve 84 will close before long. The spring 88 may be so designed that the valve will close at a pressure of about five pounds. The closure of valve 84 shuts off the supply of water to the boiler, which tends to prevent an excessive rise in boiler pressure and avoids the waste of water in case there is some delay in beginning work with the iron.

70 When the ironing operation begins, the operator presses forward on knob 111 with his thumb,

which actuates lever 110 to open the steam valve 34, and steam begins to flow through the valve into channel 5 in the sole plate and out through the openings 6 in the toe of the iron. On entering channel 5 the steam flows through the sole plate to the rear and then returns to the toe of the iron before passing out through the openings 6. The passage of the steam through the hot sole plate insures that only dry steam will be delivered to the material being ironed. The steam valve may be operated intermittently or may be held open for substantial intervals as required. As the steam is used, the pressure in the boiler falls, whereupon the valve 84 opens to admit more water. During continuous ironing operations this valve will remain open most of the time, but if any suspension of operations occurs, the valve responds to the resulting rise in steam pressure and shuts off the water. This makes it unnecessary to close the manually operated valve 76 until the ironing is completed, even if the work is interrupted from time to time.

As previously mentioned, the steam valve is so constructed that it also operates as a safety valve. The valve is enabled to function in this manner because the steam pressure inside the boiler tends to open the valve against the tension of spring 30. This spring may be so adjusted that the valve will open at a boiler pressure of about eight pounds. With this adjustment the valve ordinarily will not open automatically, because the automatic shutoff valve 84 cuts off the water supply when the pressure reaches five pounds. If anything should go wrong with the shutoff valve, however, or if the heat adjustment is too high, the pressure may increase sufficiently to open the steam valve. It will be seen, therefore, that the iron is entirely safe. The dual functioning steam valve is particularly reliable in performing its function of a safety valve because it is in continuous use under manual control and is always free and operative; or, at least, if anything goes wrong with it, the fact will immediately become apparent. This overcomes the objection to a separate safety valve, which operates very infrequently, and may become stuck and remain that way without its condition becoming known.

When the iron is to be put away, the cord is disconnected and the water is shut off at valve 76 to prevent flooding of the boiler as the temperature goes down. The tank need not be emptied.

The location of the channel 5 in the sole plate is of special importance, particularly when working on certain fabrics, such as silk and rayon, which have to be ironed with a relatively low sole plate temperature, say about 225°. This temperature is considerably below the temperature at which the heating element can maintain the iron, and consequently the thermostatic control will come into play from time to time to shut off the heat. The bi-metallic element 134 is located where it is affected by the sole plate temperature, which changes rather slowly due to the large mass of the material of which it is composed. It is desirable to accelerate the change in temperature in the vicinity of the element 134, to give a quicker and more accurate control, and decrease the length of the intervals during which the heat is off, thus avoiding any danger of water accumulating in the boiler. To this end the channel 5 is directed to the rear of the sole plate close alongside the recess in which the bi-metallic element 134 is located. At any time when the heat is off and while the iron is in use, the opening of 75

the steam valve permits the flow of steam along the channel 5, which cools the sole plate somewhat and causes the element 134 to turn on the heat again sooner than would otherwise be the case. 5 Although the steam is hot it still has a somewhat lower temperature than the sole plate, so that the described effect will take place. The effect is greatly enhanced if the operation reaches the critical stage where moist steam begins to 10 leave the boiler, indicating an imperative demand for heat, which is met at once by the loss of heat of evaporation and consequent rapid reduction of the sole plate temperature in the vicinity of the bi-metallic element to the point where the element will reclose the circuit of the heating element.

The modified form of the invention, which is shown in Fig. 6, will now be described. The object of this modification is to combine the 20 manually operated shutoff valve and the automatic shutoff valve in one structure, or, in other words, to simplify the iron by providing a dual-purpose valve which may be manually controlled and is also controlled automatically responsive to a rise in boiler pressure.

The iron shown in Fig. 6 is the same as the one shown in Figs. 1-5, except that the manually controlled valve 76 at the side of the tank, together with the shoulder 73, is entirely omitted 30 and is replaced by a new valve structure at the rear of the tank which incorporates both the manual and automatic control feature. There are other minor changes in the tank structure, which will be apparent. That part of the drawing Fig. 6 which is shown in section is on the line 6—6, Fig. 2.

The bottom of the tank 61' is cast with a downwardly-extending annular rim 150, which is bored out to receive the diaphragm 154. The 40 diaphragm 154 is clamped between two gaskets against the shoulder in annular rim 150 by means of the cup-shaped member 152, which is attached to the rim 150 by means of several screws such as 151. The member 152 is vented at the center 45 so that the space inside is at atmospheric pressure. A coil spring 153 is housed in member 152 and presses against the center of the diaphragm 154. The space 155 above the diaphragm is connected by a diagonal passage 82' with the space 50 at the end of the hollow screw 65'.

Just above the center of the diaphragm 154 there is an opening drilled through the bottom of the tank. This opening is countersunk on the inside to form a seat for the valve 158. The 55 valve is formed at the lower end of the rod 157, which continues beyond the valve in the form of a stem 156 of reduced diameter the end of which bears against the head of a rivet set in the center of the diaphragm. The rod 157 also includes an upper section 160 of reduced diameter which is surrounded by coil spring 159. The 60 manually operated part of the valve comprises a shaft 161, which is rotatable by means of knob 163. The shaft 161 is threaded at its lower end 65 in an abutment formed in the tank wall. The shaft is surrounded by packing, held in place by the gland 162. The upper section 160 of rod 157 enters a hole drilled in the end of shaft 161.

When the valve 158 is open, water can flow 70 from the tank through the valve into the space 155 and thence by way of passage 82', hollow screw 65', the drilled openings shown, and the channel 54' to the main boiler cavity. Spring 153 tends to oppose closing of the valve, and its strength may be sufficient to prevent closing of

the valve until the boiler pressure reaches five pounds. The pressure at which the valve closes may be adjusted by means of knob 163. When the knob is rotated in a clockwise direction, the spring 159 is placed under greater compression, which partially counteracts the effect of spring 153 and allows the valve to close at a lower pressure. Rotating the knob in the other direction relieves the compression on spring 159, which causes the valve to respond only to a greater pressure. After the knob 163 has been rotated a certain distance in a clockwise direction, the bottom of the hole in shaft 161 will engage the end of extension 160, whereupon further rotation of the knob in the same direction will close the valve. It will be seen therefore, that the valve structure described comprises a valve which will respond automatically to a predetermined rise in boiler pressure to shut off the water, which can be adjusted by hand to vary the pressure to which the valve responds, and which can be closed by hand at any time.

The operation of the iron modified according to Fig. 6 is otherwise the same as the operation of the main embodiment already described.

The modification disclosed in Fig. 7 has for its main object the provision of a temperature-controlled water valve, adapted to replace the manually controlled valve such as 76. As an additional improvement the temperature-controlled valve is also controlled by boiler pressure, which enables the automatic shutoff valve 84 to be omitted. Thus the modification about to be described comprises a dual-purpose water valve controlled in accordance with the temperature of the boiler and also in accordance with the pressure in the boiler.

The valve is located at the rear of the boiler, just behind partition 9, see Fig. 2, and in line with the channel 54 in the rearwardly-extending leg 50. The channel 54 is, however, omitted, and the casting is further modified to include a raised portion 213 on the floor of the boiler cavity. The roof of the boiler is made considerably thicker at this point and is bored out from above to receive the ring 203. This ring has a transversely-extending curved arm 206. Above the ring 203 there is assembled a diaphragm 204, which is clamped in place between two gaskets by means of the threaded cup-shaped closure member 214, the latter having a hexagonal head at the center by means of which it can be screwed down tightly. The member 214 is drilled and tapped at the center to receive the screw 211. A spring 210 is tensioned between this screw and the diaphragm 204.

On the lower side of the diaphragm there is secured a bimetallic element 202 which may be shaped as shown in the drawings. The lower horizontal portion of the element 202 is perforated to admit the body of the valve 209, and the stem of the valve passes up through an opening in arm 206. The valve is urged to its seat by a light spring 205 secured to arm 206. The element 202 is normally under compression, the end of the element bearing against the edge of the ledge 213.

The passage 200 is drilled out from the rear of the boiler and is plugged at the end by means of a screw 201. This passage connects with passage 66 at the rear. The passage 200 extends forward past the center of diaphragm 204, and is tapped by an opening drilled down through ledge 213 from above. This opening is countersunk to provide a seat for valve 209. The valve is nor-

mally held closed by gravity and by the spring 205. Screw 211 is an adjusting screw for varying the boiler pressure to which the valve is responsive and is accessible through an opening 212 in the cover 60.

Describing the operation of this modification briefly, when the tank is filled no water can pass to the boiler because the valve 209 is closed. When the iron is connected to a source of current, it begins to heat up, likewise the bi-metallic element 202, which gradually loses its tension and eventually bends upward to raise the valve 209. The bi-metallic element should preferably be arranged to open the valve responsive to a temperature of about 215 degrees. When the water is first admitted, the parts will be cooled down somewhat, and the valve may close, but will soon open again as the heating continues and the water is converted to steam. The valve will therefore feed water to the boiler only at times when the temperature is high enough to convert the water to steam and positively prevents flooding of the boiler with water.

As in the case of the main embodiment of the invention, if the steam is not discharged by opening the steam valve, the pressure in the boiler will rise and eventually will exert a force on diaphragm 204, which is sufficient to bend the diaphragm outwardly against the tension spring 210. The adjustment of this spring may be such that a pressure of about five pounds is required for operation, as in the previous case. The horizontal portion of the bi-metallic element 202 is now resting against the end of arm 206, holding valve 209 open, but when the diaphragm 204 rises it carries along the element 202, or attempts to do so, and the horizontal portion of the element acts about the end of the arm 206 as a fulcrum to close the valve. That is, the diaphragm raises all that part of the bi-metallic element to the right of the fulcrum at the end of arm 206 and consequently the end of the element to the left of the fulcrum point is lowered and the valve is closed. When the consumption of steam begins the pressure within the boiler falls, the diaphragm 204 returns to normal and the valve 209 is opened again, provided, of course, that the temperature has been maintained.

Referring now to Fig. 8, there is shown a cap which may be substituted for the cap 100 of Fig. 50 1 as a closure for the water tank. The modified form of cap comprises a main threaded body portion 250, having a hexagonal shoulder 252 by means of which it can be screwed tightly into the tapped opening at the top of the tank. The body 55 250 has a longitudinal bore, in which is located a check valve in the form of a ball 251, held in its seat by a light coil spring 258. A tube 251 is threaded into the lower end of 250. At the upper end of the body member 250 there is inserted a 60 curved tube 255. This tube is provided with a shoulder 254, which is held against the end of 250, with a gasket interposed, by means of a clamping nut 253. By loosening this nut the tube 255 can be turned in any desired direction.

65 The reference character 256 indicates a rubber hose which leads to a main supply tank from which the water is fed to the tank in the iron by gravity. The height of the tank should be sufficient to develop a head of about three pounds. 70 When the water is turned on at the supply tank, the water will flow through the hose and valve 251 in the cap, filling the tank in the iron. Some time before the water level reaches the top of tube 12, however, the air in the tank and boiler

will be compressed enough to build up a pressure which will stop the flow of water, the steam valve being closed. When water is admitted to the boiler, steam will be generated which maintains the pressure. As the iron is being used the steam valve will be opened at intervals and at such times the pressure in the boiler and tank will fall far enough so that water can enter through valve 257. Thus the tank may be kept supplied with water during continuous use over long periods, which is especially desirable when the iron is in service in a laundry.

The cap shown in Fig. 8 is also desirable in the ordinary domestic use of the iron to facilitate refilling. Unless some care is taken in removing the cap 100, Fig. 1, there is danger of burning by hot steam, a difficulty which is avoided by the modified form of cap, since it does not have to be removed. Removal of the cap is unnecessary because of the passageway including the tube 255 and valve 257, through which water may be introduced in any suitable or desired manner.

The invention having been described, that which is believed to be new and for which the protection of Letters Patent is desired will be pointed out in the appended claims.

I claim:

1. In a steam iron, a sole plate, a boiler superimposed on said sole plate and secured thereto with a heating element between them, a thermostatic device in said sole plate to control said heating element, said device comprising a bimetallic strip disposed lengthwise of the sole plate, steam outlets in the face of the sole plate, a valve-controlled steam passage leading from the boiler to the sole plate at a point near the toe thereof, and a channel in the sole plate through which the steam is conducted to the said outlets over a path which extends rearwardly parallel and close adjacent to said device, whereby the response of the device to a demand for heat is accelerated.

2. In a steam iron, a sole plate, a boiler superimposed on said sole plate and secured thereto with a heating element between them, a thermostatic device in said sole plate to control said heating element, a steam passage leading from the boiler to the sole plate, a manually controlled valve in said passage, and a steam channel in the sole plate leading to outlets on the face thereof, a part of said channel ahead of the said outlets being so related to the said device that in case moist steam is admitted through said valve the evaporation of the water in said moist steam will draw heat from the sole plate in the immediate vicinity of the device and accelerate the response thereof.

3. In a steam iron, a sole plate having a central recess therein for a thermostatic device, a steam channel in said sole plate starting at a point forward of said recess and extending in two branches to the rear of the sole plate, said branches being located on opposite sides of said recess in good heat transfer relation to the device therein and after reversing at the rear of the sole plate extending forward to the toe of the iron where they join, steam outlets adjacent the junction of said branches, a boiler superimposed on said sole plate, and a steam passage leading from the boiler to the channel and connecting therewith where the channel starts.

4. In a steam iron, a sole plate, a boiler superimposed on said sole plate, a heating element between the boiler and sole plate, a one-piece

5 casting comprising a cover enclosing the boiler and heating element and a water tank in the rear of said boiler, said boiler including an integrally formed extension which projects to the rear beneath the tank portion of said casting, means for securing said tank to said extension, and means including passages in said extension for establishing communication between the boiler and tank.

10 5. In a steam iron, a sole plate and boiler in superimposed relation, a heating element common to said boiler and sole plate, a cover of cast material enclosing the boiler and heating element, a terminal strip for making electrical connections to said element, and a water tank in the rear of and above the boiler, said tank being cast integrally with the said cover and having a recess in the front thereof to form a housing for said terminal strip.

15 6. In a steam iron, a sole plate, a boiler superimposed on said sole plate and having a solid extension in the rear thereof, a water tank supported on said extension and secured thereto by hollow screws, and passageways connecting the 20 interior of the boiler with the interior of the tank including said screws and holes drilled in said boiler extension.

25 7. In a steam iron which includes a boiler and a water tank, a water passage leading from the tank to the boiler, a normally closed valve in said passage, means for heating said boiler, and means responsive to the boiler temperature rising to a predetermined point for opening said valve.

30 8. In a steam iron which includes a boiler and a water tank, a water passage leading from the tank to the boiler, a normally closed valve in said passage, and a thermostatic device including a bi-metallic strip for opening said valve responsive to a predetermined boiler temperature.

35 9. In a steam iron which includes a boiler and a water tank, a water passage leading from the tank to the boiler, a normally closed valve in said passage, means for heating said boiler, 40 means for opening said valve responsive to the boiler temperature rising to a predetermined point, and means for closing said valve while the temperature remains above the opening point responsive to the pressure in the boiler increasing to a predetermined extent.

45 10. In a steam iron, a boiler, a tank from which water is fed to the boiler automatically, means including a thermostatic device for starting the feed of water responsive to a predetermined boiler temperature, and means for stopping the feed responsive to a predetermined boiler pressure.

50 11. In a steam iron, a boiler, a water tank, a passage leading from said tank to said boiler, a second passage for maintaining the pressure above the water in said tank equal to the boiler pressure, a valve in said first passage, a flexible diaphragm set in the wall of the boiler for controlling said valve, and means including said diaphragm for closing said valve responsive to the boiler pressure rising to a value which exceeds the atmospheric pressure by a predetermined amount.

55 12. In a steam iron which includes a boiler and a tank for supplying water to the boiler, a closure member for said tank, a passage extending through said member for filling the tank, and a check valve in said passage.

60 13. In a steam iron, a sole plate, a boiler super-

imposed on said plate, a steam valve for controlling the flow of steam from the boiler to the sole plate, a cover for the boiler, a handle and means for securing it to the iron including a bracket attached to said cover, means for controlling said valve including a bell crank lever pivoted on said bracket and located entirely in front thereof, a knob for actuating said lever, and a detachable recessed fore cap for the handle partially enclosing said lever.

14. In a steam iron which includes a boiler and a water tank, a water passage leading from the tank to the boiler, a valve for controlling the flow of water through said passage, a thermostatic device for opening said valve to admit water to the boiler, a passage for communicating boiler pressure to the tank, and means for closing said valve responsive to the said pressure rising to a predetermined point above atmospheric pressure.

15. In a steam iron, a boiler, a sole plate, a passage for conveying steam from the boiler to the sole plate, a normally closed manually controlled steam valve in said passage, a water tank, a passage for conveying water from said tank to said boiler, a water valve in said last mentioned passage, said water valve being closed when the iron is cold, means for heating the iron and boiler, temperature responsive means for opening said water valve upon a predetermined temperature rise, and means for automatically closing said water valve in response to excessive boiler pressure due to continued closure of said steam valve.

16. In a steam iron, a boiler, a sole plate, a water tank, an automatic water valve for controlling the flow of water from the tank to the boiler, said valve being adjusted to shut off the water upon a predetermined rise in boiler pressure, and an automatic valve for controlling the flow of steam from the boiler to the sole plate, 40 said last mentioned valve being adjusted to open at a predetermined boiler pressure which is greater than the pressure required to close said water valve.

17. In a steam iron, a boiler, a water tank for supplying water to said boiler, means for heating said boiler to generate steam, means including a valve for automatically shutting off the water supply to the boiler upon a predetermined rise in steam pressure, and thermostatically controlled means for automatically effecting closure of said valve when the heat is turned off to prevent flooding the boiler.

18. In a steam iron, a sole plate, a boiler, a water tank, a passage for conveying water from said tank to said boiler, a passage for transmitting boiler pressure to said tank, a passage for conveying steam from the boiler to the sole plate of the iron, a steam valve in said last mentioned passage, a water supply pipe extending to said tank from a water supply source under pressure tending to deliver water to the tank, and a check valve operatively interposed between said tank and the water supply source for preventing a reverse flow of water in case the boiler pressure rises above the water supply pressure due to failure to open said steam valve.

19. In a steam iron which includes a boiler and a tank for supplying water to the boiler, said iron having a water passage extending from the tank to the boiler, a passage for communicating steam pressure in the boiler to the tank at a point above the level of water therein, a water supply pipe for delivering water to the tank under pressure, said pipe terminating inside the tank

below the water level, and a check valve in said pipe for preventing a reversal of water flow in case the steam pressure rises higher than the water pressure.

5 20. In a hand operated steam iron, a boiler and a water tank both supported on and movable with the rest of the iron, a water passage leading from the tank to the boiler, a valve in said passage, means for maintaining equal pressures 10 in the boiler and tank independent of said passageway, a diaphragm forming part of the wall of said passageway and subject to the pressure of the water therein, such water pressure being due to the steam pressure in the boiler acting 15 on the water in said passageway, and means whereby said diaphragm is operative to effect closure of said valve in response to a predetermined pressure of the water in said passage.

21. In a steam iron adapted for manipulation by hand, a boiler and a water tank both supported on and forming part of the iron, the said boiler and tank being so arranged on the iron that the bottom of the tank cavity is approximately level with the bottom of the 25 boiler cavity, a passage leading from the tank to the boiler, means independent of said passage for maintaining equal pressures in the tank and boiler to permit the flow of water through said passage by gravity, a valve for closing said passage to stop the water flow, and means including a diaphragm responsive to the boiler pressure for controlling said valve.

22. In a hand manipulated steam iron, a boiler and a water tank both supported on and forming part of the iron, means for maintaining equal pressures in said tank and boiler, a passage for transferring water from the tank to the boiler by gravity, said passage including a water retaining cavity which is below the level of both the boiler and tank and hence is incapable of draining into either the boiler or tank, a valve for closing the said passage, and means including a diaphragm in contact with the water in said cavity and responsive to the pressure of the steam in said boiler transmitted to the said diaphragm through the water in said cavity for operating said valve.

23. In a hand operated steam iron, a boiler and a water tank secured together and movable as a unit with the remainder of the iron, said tank having a recess formed in the exterior bottom wall thereof, a diaphragm closing said recess, means including a valve for admitting water from the tank to said recess, a passage for conducting water from said recess to said boiler, and means whereby said diaphragm is adapted to effect closure of said valve responsive to the pressure in said recess communicated thereto from the boiler via said passage.

60 24. In a steam iron, a sole plate, a boiler superimposed on said sole plate and secured thereto, a heating element between said boiler and sole plate, a one-piece casting comprising a water tank for supplying water to the boiler and a cover enclosing said boiler and heating element, the cover portion of said casting having a rim which rests on the sole plate and the tank portion of the casting having a part engaging a corresponding part of the boiler, means for establishing communication between the tank and boiler through said parts, and means for securing said casting to the boiler, including means for clamping said parts together.

65 25. In a steam iron, a sole plate, a boiler superimposed on said sole plate, a heating ele-

ment between said boiler and sole plate, a cover of cast material cooperating with said sole plate to enclose the boiler and heating element, a water tank cast integrally with said cover, said tank being located to the rear of the boiler and including a portion which extends upwardly from the rear of the cover portion of the casting, said tank also including a portion cooperating

5 with the boiler through which communication between the boiler and tank is established, a handle for the iron, and means for securing said handle to the forward end of said cover and to said upwardly extending portion of said tank.

STANLEY WALLACE.
